OIL RESERVOIR FOR TRACTORS OR THE LIKE

John L. Aldred, Jr., Bloomfield Hills, Mich., assignor, by
mesne assignments, to Ford Motor Company, a corpora-
tion of Delaware

Filed Dec. 7, 1959, Ser. No. 58,572

Term of patent 14 years

(Cl. D77—1)

Fig. 2

Fig. 3

FIGURE 1 is a side elevation of an oil reservoir for tractors or the like, showing my new design.

FIGURE 2 is an end elevation thereof; and

FIGURE 3 is an elevation thereof as seen from the opposite side of FIGURE 1.

I claim:

The ornamental design for an oil reservoir for tractors or the like, as shown.
